SHEET FASTENING DEVICE

Willis W. Karlen, Vilas, S. Dak.

Application: March 10, 1924 Serial No. 510,261

6 Claims. (Cl. 129—25)

The principal object of my invention is to provide a sheet fastening device that is capable of holding two separate groups of sheets.

A further object of this invention is to provide a sheet fastening device adapted for use in combination with the ordinary folder having a center fastening tang flap that permits the tang of the folder to be comparatively narrow in width, thereby reducing the combined thickness of the folders when in their file cabinet.

A still further object of my invention is to provide a sheet fastening and holding clasp for use in connection with folders having a central fastening tang flap that permits the securing of the clasp element on the flap of the folder without danger of the clasp element becoming accidentally torn therefrom.

A still further object of my invention is to provide a sheet fastening device that is stamped from a single sheet of material.

A still further object of this invention is to

provide a sheet fastening device that is economical in manufacture and durable in use.

These and other objects will be apparent to
25 those skilled in the art.

My invention consists in the construction, arrangement and combination of the various parts of the device, whereby the objects contemplated are attained as hereinafter more fully set forth, 30 pointed out in my claims and illustrated in the accompanying drawing, in which:

Fig. 1 is a bottom plan view of my sheet holder secured to the ordinary tang flap of a folder.

35 Fig. 2 is a front marginal edge view of my device secured to a folder and showing the sheet receiving positions of the four arms in dotted lines.

Fig. 3 is a top plan view of my device secured to the tang flap of a folder.

Fig. 4 is a bottom plan view of my sheet securing clasp after it has been stamped from a sheet of suitable material and before it has been bent and folded.

45 Fig. 5 is an end view of my device taken on line 5-5 of Fig. 2, and more fully shows its construction.

Referring to the drawing, I have used the numeral 10 to designate the ordinary paper or like folder to which my device is secured. This folder 10 is folded back upon itself near its center and then reversely folded to form the usual center tang flap 11, the folds of the flap preferably being secured together. In the art it is the practice to secure the sheet attaching fas-

tener to this flap and my device is no exception to this practice, as will be noted in the drawing. The elongated base portion of my device is designated by the numeral 12. This portion before bending and as shown in Fig. 4, is of flat rectangular construction.

The numerals 13 and 14 designate two comparatively short clamping tongues integrally formed on the two ends respectively of the portion 12. These two tongues extend in opposite directions from each other and are located in a plane near the inner or rear side edge of the portion 12. The numerals 15 and 16 designate two comparatively long arms integrally formed on the two ends respectively of the base portion 12. The two arms extend in opposite directions from each other and are located in a plane near the front side edge of the portion 12 and before the same is bent onto the folder, as shown in Fig. 4.

The numerals 17 and 18 designate two arms similar to the arms 15 and 16 which are also integrally formed on the two ends respectively of the base portion 12. These arms are parallel with the arms 15 and 16 and are positioned in spaced relationship between the arms 15, 16 and the tongues 13, 14. This sheet fastening device, as shown in Fig. 4, is made of any suitable material such as bendable sheet metal, and after being stamped out as shown, is ready to be attached to the tang flap 11. To accomplish this the tongues 13 and 14 are bent at right angles to the base 12 and are inserted through the two spaced apart slots 19 in the tang flap 11, after which they are clinched inwardly to a flat condition, as shown in Fig. 3, thereby rigidly securing the base 12 to the under side of the tang flap. The slots 19 should be in close proximity of the base folds of the flap 11, as shown in Fig. 1, in order to eliminate any possibility of the metal sheet holder being torn from the folder by usage. This desirable securing of the sheet holder a substantial distance from the free marginal edge of the flap 11 is possible by the construction of my device.

The width of the base 12 relative to the flap 11 when the two are secured together should be such that the arms 17 and 18 normally rest under the flap 11 and the free marginal edge of the flap rests in a plane between the two planes of the arms 17, 18 and 15, 16. With this condition existing the base 12 is bent on and around the free marginal edge of the flap 11, to bring the arms 15 and 16 to rest on top of the flap 11, as shown in Fig. 3. By this resultant position of

elements there are two arms (17 and 18) for securing sheets below the flap 11 and two arms (15 and 16) for securing sheets above the flap 11. To attach the sheets which are usually sheets of paper with indicia thereon, the arms are bent outwardly from the flap 11 as shown in dotted lines in Fig. 2, and then are again bent downwardly to rest in flat condition after they have pierced the sheets to be held. After the sheets have been properly attached the two backs of the folder 10 are folded together with the sheets between them. It will be found that the result is a highly desirable one and that the folder will lie flat and compact, thereby conserving space in the file cabinet. By the tongues 13 and 14 engaging the flap 11 near its secured edges the flap may be of minimum width, which is not possible in other devices of this class now being used by the general public.

Although I have described my device as used in combination with folders having attaching tang flaps, it may be used successfully in other set-ups.

Some changes may be made in the construction and arrangement of my improved sheet fastening device without departing from the real spirit and purpose of my invention, and it is my intention to cover by my claims any modified forms of structure or use of mechanical equivalents which may be reasonably included within their scope.

I claim:

1. In a device of the class described, a rectangular base member bent upon itself to form a lower and an upper portion, two arms on the said upper portion, two arms on the said lower portion, and two attaching tongues on the said lower portion.

2. In combination with a folder or the like bent back upon itself and then reversely folded to form a tang flap, a base member folded on and around the free marginal edge of said tang flap, a means for rigidly securing said base to said tang flap, arms secured to that portion of said base that is on the upper side of said flap, and

arms secured to that portion of said base that is on the under side of said flap.

3. In combination with a folder or the like bent back upon itself and then reversely folded to form a tang flap, a base member folded on and around the free marginal edge of said tang flap, tongues on said base and extending through said flap for securing said base to said tang flap, arms secured to that portion of said base that is on the upper side of said flap, and arms secured to that portion of said base that is on the under side of said flap.

4. In combination with a folder or the like bent back upon itself and then reversely folded to form a tang flap, a base member folded on and around the free marginal edge of said tang flap, two fastening tongues on the portion of the base member resting below the said flap and extending through said flap for securing said base to said flap, and two spaced apart arms on the part of the base member above said flap designed to receive and hold sheet members.

5. In combination with a folder or the like bent back upon itself and then reversely folded to form a tang flap, a base member folded on and around the free marginal edge of said tang flap, fastening tongues on the portion of said base member below said flap; extending through said flap and positioned a substantial distance from the free marginal edge of said flap, sheet holding arms on said base member and below said flap, and sheet holding arms on said base member and above said flap.

6. In combination with a folder or the like bent back upon itself and then reversely folded to form a tang flap, a base member folded on and around the free marginal edge of said tang flap, and rigidly engaged with opposite sides of said flap for cooperation therewith to retain said base member on said flap, arms secured to that portion of said base that is on one side of said flap, and arms secured to that portion of said base that is on the opposite side of said flap.

WILLIS W. KARLEN.
